ADJUSTABLE GRILLE

James P. Burcham, Indianapolis, Ind.

Application April 13, 1934, Serial No. 720,396

3 Claims. (Cl. 20—71)

This invention relates to a grille for serving as a guard or protection in connection with windows and similar openings, screen doors and the like, particularly wherein said grille is adjustable 5 within limits as to the length thereof.

The principal object of the invention is to economically produce a grille of the above character which is adjustable while having qualities present in a fixed grille, such as vertical bars 10 mounted in conjunction with the grille structure.

One feature of the invention resides in the mounting of the rigid, vertical bars slidably connected with the adjustable frame and the adjustable grille.

15 Another feature of the invention resides in the removable anchorage devices for securing the rigid bars to the adjustable grille but permitting a sliding relation therebetween.

A further feature of the invention resides in 20 the arrangement of the adjustable frame wherein there is provided a central section into which the end sections are adapted to telescope.

Still a further feature of the invention resides 25 in the slidable anchorage devices secured to the pivoted grille bars slidably supported within the frame, all as will be hereinafter more specifically set forth and described.

Other objects and features of the invention will 30 be understood from the accompanying drawing and the following description and claims:

Fig. 1 is a plan view of the grille. Fig. 2 is an enlarged section taken on the line 2—2 of Fig. 1. Fig. 3 is an enlarged section taken on the line 3—3 of Fig. 1. Fig. 4 is an enlarged elevation 35 of that portion of the invention illustrated in Fig. 2.

In the drawing there is illustrated a longitudinal adjustable grille comprising end frame sections 10, upper and lower end sections 11 and 40 upper and lower central sections 12. The sections 10 and 11 are rigidly secured together by rivets 13 at the corners of the frame and are provided with longitudinal slots 14 on the inner surface thereof. The central sections 12 are correspondingly formed, but enlarged to slidably receive the sections 11 therein. Thus, the ends 45 of the frame may be moved relative to the central sections 12 telescoping in each end thereof.

Extending intermediate the upper and lower sections 11 and 12 there are a plurality of vertical rigid bars 15 having their ends extending through 50 the slots 14 of the upper and lower sections so as to be slidable longitudinally thereof. The central bar indicated at 15a is rigidly secured

intermediate the ends of the sections 12 for anchoring the grilles and bars centrally of the frame. At intervals throughout the length of the bars 15 there are flattened portions 16 where the bars extend between the members of the grille. 5

The grille comprises a plurality of angularly disposed members 17 which crisscross each other as illustrated and are pivotally connected by rivets or screws 18 intermediate their ends, such pivotal connections extending in a horizontal line 10 intermediate the top and bottom of the frame. The free ends of said members are provided with longitudinal slots 19 for receiving a removable locking plate 20 which is provided with recesses 15 intermediate its head portions 21 and its body portion. The body portion is provided with an opening through which the bars 15 may extend as illustrated in Fig. 2.

In assembling the grille members and bars as shown in Fig. 3, the locking plate 20 has its heads 20 21 inserted through the slots 19 when the members 17 lie parallel with each other. After the heads 21 have passed through the slots, the plate may be turned to the position illustrated in Fig. 4 and the bars 15 inserted through the opening 25 in the body of the plate so as to be slidably connected with the grille members.

As will be noted in Fig. 1, the flattened portions 16 extend between the intersecting members of the grille so as to permit relative sliding movement therebetween. 30

While the upper and lower ends of the grille members are pivotally connected through the medium of the plate 20, the ends projecting laterally into the end sections 10 of the frame are 35 pivotally connected to a cup 23 as shown in Fig. 3, said cup being provided with flanges which slide within the frame sections 10 while retaining the pivoted ends of the grille members therein. This arrangement provides both a pivotal connection 40 for the grille members and a bearing for slidably supporting them within the end bars.

In operation, the grille may be adjusted longitudinally within limits by pushing the end sections 10 of the frame toward and away from each 45 other. When they are pushed toward each other, the bar 15a remains at a fixed position while all the other bars 15 are caused to slide horizontally toward the central bar through their sliding connection with the grille members. The grille members vary their angular relation to each other, the upper and lower free ends sliding longitudinally of the bars 15 through the medium of the plate 20 which also permits them to alter their angular relation. This action also causes the 55

upper and lower end mountings or cups 23 to slide within the end sections 10 away from each other. The reverse action takes place upon lengthening the grille by pushing the end members 5 10 of the frame away from each other, thereby drawing the plates 20 toward the center of the bars 15 and causing a corresponding movement of the bearing cups 23 in the inner section of the frame.

10 The invention claimed is:

1. A grille comprising a rectangular frame having a plurality of frame sections telescoping one within the other, a plurality of rigid bars mounted in spaced parallel relation to each other with their free ends slidably mounted with respect to said frame sections, a plurality of interwoven grille members angularly disposed in relation to each other and said bars, each of said bars being slidably embraced between said grille members at 20 their points of intersection, and a locking plate mounted on said grille members to slidably embrace and retain said bars in relation thereto.

2. A grille comprising a rectangular frame having upper and lower frame sections telescoping one within the other, each of said sections having a slot formed longitudinally and opening inwardly thereof, a plurality of rigid bars mounted 25

in spaced parallel relation to each other having their free ends extending into said slots, a plurality of angularly disposed interwoven grille members slidably embracing said bars at their points of intersection, and a plate pivotally connected to the upper and lower free ends of said members through which said bars extend for slidably interlocking said bars and members.

3. A grille comprising a rectangular frame having a plurality of frame sections, some of which telescope one within the other, a plurality of rigid bars mounted in spaced parallel relation to each other, a plurality of angularly disposed interwoven grille members adapted to embrace said bars at their points of intersection, the free ends 10 of said members between which said bars are adapted to pass having longitudinal slots therein, and a plurality of plates having enlarged heads thereon adapted to extend through adjacent slots 15 when said grille members are arranged in parallel relation while permitting said members to be moved to angular relation, thereby causing the interlocking of said plates therewith, said plates having openings through which said bars extend 20 for interconnecting the bars and grille members 25 in slidable relation.

JAMES P. BURCHAM.
